UNITED STATES PATENT OFFICE.

ADAM L. SMITH AND THOMAS F. RUSSELL, OF YOUNGSTOWN, OHIO.

DOORSTRIP.

Application filed September 1, 1921. Serial No. 497,592.

To all whom it may concern:

Be it known that we, ADAM L. SMITH and THOMAS F. RUSSELL, citizens of the United States, and residing in the city of Youngstown, in the county of Mahoning and State of Ohio, have invented or discovered new, useful, and Improved Doorstrips, of which the following is a specification.

Our invention consists in a new and improved automatic door strip for closing the crack or space between the bottom of the door and the sill plate or floor.

Where the bottom of a door is provided with a fixed strip, the latter, if snug enough to close the crack when the door is closed, usually interferes with the opening and closing of the door by dragging or scraping over the floor or floor covering. Thus, in the case of hard wood or finished floors, a rug cannot be kept in place near the door because it will be shoved away or disarranged when the door is opened and closed.

The object which we have in view is the provision of an improved door strip which will effectively pack the crack or opening under the closed door, but will in nowise interfere with the convenient opening and closing of the door.

For this purpose, we provide a door strip member which is mounted on the door in such a manner as to be capable of vertical movement, and means whereby when the door is closed the strip is depressed into packing engagement with the door sill but when the door moves out of its closed position the strip is elevated so as to clear the floor or floor covering.

In the accompanying drawings, which are however merely intended to illustrate the principles of our invention without limiting the scope of the latter to the construction shown, Fig. 1 is a view in elevation of the lower portion of a closed door fitted with a door strip embodying the principles of our invention, the cover plate being however omitted to more clearly show the structure; Fig. 2 is an enlarged sectional view taken along the line II—II in Fig. 1; Fig. 3 is an edge view of the door, showing the elevated position of the strip when the door is out of its closed position; Fig. 4 is a section taken along the line IV—IV in Fig. 1; Fig. 5 is an elevation of the lower portion of a door showing a modified form of door strip construction, the figure being broken and one side, the left, showing the door closed,

while the other side shows the door open, the strip being thus shown both in its depressed and elevated positions in the one figure; Fig. 6 is a sectional view taken along the line VI—VI in Fig. 5, while Fig. 7 is a similar view taken along the line VII—VII in Fig. 5.

The following is a detailed description of the drawings, reference being first had to the first four figures of the same.

A represents a door hinged in the usual manner, as at 1, to the vertical edge of the door frame B. C represents the door sill which forms the threshold of the doorway.

2 is a metal face plate attached to the face of the door at its bottom and on the side toward which the door opens. 3 represents two or more guide brackets secured at their upper ends to the face plate 2 and bent to extend down in front of the door and spaced therefrom. D represents the door strip member, which may be either a wooden board or a metal plate and which is mounted for vertical movement between the guides 3 and the plate 2. The bottom of the door strip is slotted to receive the packing strip 4, which may be of felt, rubber or other suitable compressible material to make a snug, compressed contact with the sill C when the door is closed, and thus exclude the air from passing under the door.

5 represents two or more slots or recesses cut down through the top edge of the door strip to provide clearance for the horizontal heads of the bracket members 6 which are attached to the plate 2. 7 represents small metal plates attached to the top edge of the door strip D and thus closing the upper ends of the recesses 5. The bracket heads 6 and the plates 7 are pierced with alined holes through which extend the bolts 8, and 9 represents helical springs coiled about said bolts, their upper ends bearing on the plates 7 while their lower ends bear on the heads of brackets 6. The springs thus tend to elevate the door strip D into the position shown in Fig. 3.

E represents a shaft horizontally journaled on the face of the plate 2 by means of bracket bearings 10 above the strip D, said strip being notched, as at 11, to provide clearance for its free movement. 12 represents two or more toe-bars fixed radially on the shaft E and provided with eccentrically disposed arcuate contact surfaces which engage the top edge of the strip D and act to

depress said strip from the position shown in Fig. 2 to that shown in Fig. 3, when the shaft E is rocked in the proper position.

We prefer to provide the upper edge of

5 the strip D with metal contact plates 13 which are engaged by the toe-bars 12 to prevent wear, and such contact plates are preferably provided with bevelled top surfaces to assist in the function of the toe-bars.

10 The end of the shaft E toward the free edge of the door, the left edge in Fig. 1, is provided with a radial lever 14, fixed to said shaft and provided at its free end with a roller 15 which is adapted to come into contact with the door frame as the door reaches its closed position. The relative angles of

15 the toe-bars 12 and the lever 14 are such that, when the door strip D is raised by the springs 9, the lever 14 is inclined in the position shown in Fig. 3 so that the roller 15 will come into contact with the door frame just before the door reaches its closed position.

20 The result is that as the door closes the lever 14 is forced upwardly toward a vertical position, thus forcing down the toe-bars 12 and depressing the door strip from the position indicated in Fig. 3, wherein it is elevated, into the position shown in Figs. 1, 30 2 and 4, wherein the strip is depressed to efficiently seal the crack over the door sill.

25 In Figs. 5 to 7, inclusive, we have substituted for the wedging action of the toe-bars 12, a spur gear and rack connection between the shaft E and the door strip D. Thus we mounted on the shaft E two or more spur gears 16 which mesh with vertically disposed rack bars 17 extending upwardly from the door strip. When the shaft E is rocked 35 40 by the closing of the door, the spur gears in turning cause the strip to be depressed into its operative position.

30 In either form of the device, when the door moves out of its closed position, the springs 9 cause the door strip to be automatically elevated into its elevated position, as shown in Figs. 3 and 7, and at the right hand side of Fig. 5.

35 We have shown two convenient methods of automatically depressing the strip as the door closes, but other convenient means will suggest themselves to those skilled in the art, and we therefore do not wish to confine ourselves to the exact construction shown.

40 55 We prefer to provide a cover plate F

which is attached to the lower portion of the door and extends down over the shaft E and the door strip D, and thus conceals and protects from dirt and dust the operative parts.

60 It is evident from the foregoing that our invention provides an efficient, automatic door strip which will effectively block the entrance of air beneath the closed door but in all other positions of the door will provide for the proper clearance for the floor or floor 65 coverings.

70 Although, for the sake of clearly illustrating the principles of our invention, we have minutely described the embodiment of the same shown in the drawings, we do not 75 wish to limit ourselves thereby, but claim broadly—

75 1. In combination with a door frame and a door hinged thereto to swing on a vertical axis, a door strip mounted on the lower portion of said door and slidable vertically in relation to the latter, the said strip being provided with vertically elongated openings, 80 pierced brackets fixed to said door and extending into said openings, bolts extending through said brackets and the top walls of said openings in said strip, and helical springs coiled about said bolts between said brackets and the top walls of said openings 85 whereby said door strip is normally held elevated out of contact with the floor, and means actuated by the closing of the door and adapted to depress said door strip into contact with the door sill.

90 2. In combination with a door frame and a door hinged thereto to swing on a vertical axis, a cover plate having an inwardly extending top portion attached to the door and the vertically disposed body of said plate depending parallel to and spaced from said door, a door strip mounted between said cover plate and said door and slidable vertically, resilient means for holding said strip elevated out of contact with the floor, a rock shaft horizontally journaled in parallelism 95 with the door and inclosed by said cover plate, means whereby said shaft is rotated when said door is closed, and means whereby such rotation of said shaft depresses said door strip for the purpose described.

100 Signed at Youngstown, Ohio, this 19 day of August, 1921.

ADAM L. SMITH
THOMAS F. RUSSELL
